UNITED STATES PATENT OFFICE.

WILLIAM H. BURNETT, OF MOUND CITY, MISSOURI.

PENCIL CLIP DEVICE.

Application filed February 28, 1923. Serial No. 621,955.

To all whom it may concern:

Be it known that I, WILLIAM H. BURNETT, a citizen of the United States, residing at Mound City, in the county of Holt and State of Missouri, have invented a new and Improved Pencil Clip Device, of which the following is a specification.

My invention has reference to improvements in that class of clip devices commonly used on pencils, fountain pens and similar articles and which are especially designed for conveniently holding the pencil or pen in the pocket of the person carrying the same, and primarily my invention has for its purpose to provide an improved construction of clip device of the general character stated, stamped or otherwise formed of a spring metal blank and which, when operatively applied, will effectively retain the article in the pocket and at the same time permit its being readily removed and replaced without injury to the pocket.

Another and important object of my invention is to provide a simple, inexpensive and easily made clip device in which the members provided for gripping the edge of the pocket are especially designed to prevent side slipping of the clip along the pocket and avoid the danger of the clip being easily disconnected from the said pocket edge.

With other objects in view that will hereinafter be apparent, my invention is a pencil or pen clip device that embodies the peculiar features of construction and novel combination of parts, all of which can be explained in the following detailed description, specifically pointed out in the appended claims and illustrated in the accompanying drawings, in which:

Figure 1 is a perspective view of my improved clip device applied to a pencil and shown as held in a pocket.

Figure 2 is a plan view of the spring metal blank from which my improved clip device is shaped.

Figure 3 is a side elevation of the clip device, the parts being at their normal position.

Figure 4 is a view similar to Figure 3, the gripping or spring element being positioned to permit of fitting the clip over a pocket edge.

Figure 5 is a detail cross section, taken substantially on the line 5-5 of Figure 1

and which illustrates the manner in which the pocket edge is gripped to hold the clip devices from being readily moved laterally along or removed from the pocket edge.

Figure 6 is a detail perspective view of the clip device.

In the practical development of my improved clip device the spring metal blank shown in Figure 2, includes a body portion 1 of sufficient width and length to permit of bending the said body 1 to form a split tubular band 2 adapted for frictionally engaging the pencil or pen.

From the upper end of the body 1 the blank has a straight extension of sufficient length to permit of bending it into a spring loop 3 which, as shown, is bent to lie along the face of the band 2. The extension of the loop 3, at its upper end 30, is bent upon itself to produce a long spring clamping member 4 that extends some distance beyond the lower edge of the band 2 and terminates in an out-turned portion 40 that cooperates with an opposing gripper or clamping member 5, presently again referred to. The member 5 is also formed of an extension 50 that constitutes a part of the blank and which continues down from the lower end of the split band 2 and whose opposite edges are bent outwardly, at right angles, as at 51, to produce a channeled keeper within which the lower out-turned end of the spring clamping member 4 normally seats.

By forming the lower end of the split band with a downwardly extending keeper that has side edges 51, as shown, the said edges and the clamp 40 will operate to crimp the upper edge of the pocket in the manner best shown in Figure 5, from which it will be seen that the clip device is held in such locked engagement with the pocket edge so that the said clip device cannot be readily slipped laterally along the said pocket edge. Furthermore the edges 52 extend out farther at the bottom end than at the top of the keeper and thereby so securely hold the device on the pocket edge that danger of the clip becoming disconnected from the pocket is practically avoided.

From the foregoing description, taken in connection with the accompanying drawing, it will be noticed that my invention provides a clip of an exceedingly simple and inexpensive construction and which will effectively serve its intended purposes.

What I claim is:

1. A spring metal clip comprising a split sleeve, a spring member extended down over the front of the split sleeve and then back 5 up and again down to extend below the split sleeve and provide a clamping element, and a combined clamp and keeper element projected from and extended below the split sleeve and cooperative with the spring mem-

10 ber for engaging the edge of a pocket.

2. As a new article, a pen or pencil clip device bent to shape from a spring metal blank and comprising, in integral formation, a split sleeve for frictionally engaging the 15 pen or pencil, an extension from the upper end of the split sleeve that is looped downwardly from the front upper end of the split sleeve to constitute a spring loop, the upper end of the said loop being bent back 20 upon itself and extended downwardly be-

yond the lower end of the split sleeve with its free end terminating in a flat clamping element, an extension from the lower end of the split sleeve which includes oppositely disposed outwardly projected angled edges 25 that constitute a keeper into which the flattened clamped member of the spring loop sets when the parts are at the normal adjustment.

3. A spring metal clip composed of a split tubular body, a spring clamping finger extending from the upper edge of said body and back down below the lower edge of said body, a grooved keeper extending from the lower edge of said body to receive said finger, and having out-standing flanges 35 deeper at the bottom than at the top substantially as shown and described.

WILLIAM H. BURNETT.
